(57) **CLAIM**

The ornamental design for a demolition tool, as shown and described.

DESCRIPTION

FIG. 1 is an isometric view of a machine incorporating my new design, viewed from behind and from the left side of the demolition tool;

FIG. 2 is an isometric view of a demolition tool incorporating my new design, viewed from in front of and from the right side of the demolition tool;

FIG. 3 is a top plan view thereof;

FIG. 4 is a bottom plan view thereof;

FIG. 5 is rear elevation view thereof;

FIG. 6 is a front elevation view thereof;

FIG. 7 is a left side elevation view thereof; and,

FIG. 8 is a right side elevation view thereof.

The broken lines in FIGS. 1-8 are for illustrative purposes only and form no part of the claimed design.

1 Claim, 8 Drawing Sheets
